US0D1059688S

(12) **United States Design Patent** (10) **Patent No.:** **US D1,059,688 S**
(45) **Date of Patent:** **** Jan. 28, 2025**

(54) **LASH EXTENSION**

(71) Applicant: **LASHIFY, INC.**, North Hollywood, CA (US)
(72) Inventor: **Sahara Lotti**, North Hollywood, CA (US)
(73) Assignee: **Lashify, Inc.**, North Hollywood, CA (US)
(**) Term: **15 Years**
(21) Appl. No.: **29/891,867**
(22) Filed: **May 10, 2023**
(51) LOC (15) Cl. **28-04**
(52) U.S. Cl. **USPC D28/92**
(58) **Field of Classification Search**
USPC D28/9, 35, 36, 92, 93
CPC A41G 5/02; A45D 2/48
See application file for complete search history.

(57) **CLAIM**

The ornamental design for a lash extension as shown and described.

DESCRIPTION

FIG. 1 is a perspective view of a lash extension showing the new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof.

FIG. 8 is a perspective view of a second embodiment of the lash extension;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

The broken lines shown in the drawings depict portions of the lash extension that form no part of the claimed design. The lash extension is shown with symbolic breaks in its length. The appearance of any portion of the article between the break lines forms no part of the claimed design.

1 Claim, 14 Drawing Sheets
